DESIGN FOR A LIGHTING FIXTURE

Eric B. Hallman, Philadelphia, Pa., assignor to Electric Service Supplies Company, Philadelphia, Pa., a corporation of Pennsylvania

Application January 21, 1943, Serial No. 109,321

Term of patent 7 years

To all whom it may concern:

Be it known that I, Eric B. Hallman, a citizen of the United States and a resident of Philadelphia, county of Philadelphia, State of Pennsylvania, have invented a new, original, and ornamental Design for a Lighting Fixture, of which the following is a specification, reference being had to the accompanying drawing, forming a part thereof, wherein:

Figure 1 is a perspective view of the lighting fixture showing my new design;
Figure 2 is a side elevational view thereof;
Figure 3 is a bottom view thereof; and Figure 4 is an end view thereof.

I claim:

The ornamental design for a lighting fixture,
as shown.

ERIC B. HALLMAN.
